MULTICOLOR WEFT REPLENISHING LOOM

Filed Jan. 8, 1932

UNITED STATES PATENT OFFICE

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

MULTICOLOR WEFT REPLENISHING LOOM

Application filed January 8, 1932. Serial No. 585,565.

This invention relates to improvements in multicolor weft replenishing looms more particularly the transfer mechanism thereof, and it is the general object of the invention to adapt a loom of this type so that it will handle properly bobbins of different diameters.

Certain types of cloth use two different grades of filling, certain picks being relatively coarse such as cotton, and the other picks being fine, such as silk. Cotton yarn is usually wound on a relatively large bobbin, while the finer silk is usually wound on a small bobbin. As a result the conditions of transfer differ somewhat. The center of the small shuttle used for silk is noticeably lower than the axis of a cotton bobbin located in a larger shuttle, and it is an important object of my present invention to provide means for varying the throw of the transerrer arm so that it will move lower when transferring the silk bobbin than when transferring a cotton bobbin.

It is to be understood that the bobbins are held in place by springs which spread to receive a fresh bobbin, and then contract to grip and hold the same in position. The cam grooves in the springs which receive the bobbin rings are designed to hold the bobbin in a definite position, and if a bobbin should be pushed too far it could pass entirely through the springs. By my present invention the amount of movement which the bobbin receives from the transfer mechanism is regulated by the position which it will occupy in the shuttle. All the shuttles of the loom rest on the same shuttle race, and the centers of the several shuttles will be at different elevations.

It is a more particular object of my invention to provide a transerrer arm having a latch provided with two notches of different depths, so that when cooperating with the lay dagger the transerrer can be given a relatively large or small throw, depending upon the size of the bobbin being transferred.

With these and other objects in view which will appear as the description proceeds, my invention resides in the combination and ar-

rangement of parts hereinafter described and set forth in the claims.

In the accompanying drawing wherein a convenient embodiment of my invention is set forth,

Fig. 1 is a side view of the two color magazine made according to my present invention, parts being in section,

Fig. 2 is a front elevation of the structure shown in Fig. 1, and

Fig. 3 shows a shuttle and bobbin of the size different from that shown in Fig. 1.

Referring to the drawing, I have shown a loom frame 10 and a magazine M supported thereby. The magazine in the present instance is of the two-color type, having two vertical slides 11 and 12, respectively, which are suitably mounted and guided in the plate 13 of the magazine. Flanges 14 form two bobbin compartments or guideways 14a and 15, which are wide and narrow, respectively.

The upper end of each slide is provided with a spring dog 16 which cooperates with shelf 17 on a control member 18 secured to a shaft 19 which is journaled in the upper part of the magazine. An arm 20 is secured to the shaft 19 and has rotatably mounted thereon a stud 21 having a rectangular portion which slides in a slot 22 provided in a lever 23 pivoted as at 24 to the magazine frame. A spring 25 lies between a fixed part of the lever and the stud and acts to hold the control member yieldingly either in normal down, or transferring raised position. The lever has an arm 26 extending to the right as viewed in Fig. 2 to which is attached the upper end of a latch rod 27.

A transerrer arm T is pivoted as at 28 to the magazine and has depending arms 29 on which is pivoted a latch holder 30. The latch 31 may be held to the holder in any approved manner and is normally down, as shown in Fig. 1. The control rod 27 passes under the latch and is effective when raised to elevate the latch so that it will be in the path of a bunter 32, carried by the lay L of the loom.

The color slide comprises a longitudinally movable shaft or rod 40 to which is secured a casting 41 having horizontal fingers 42 one

of which is shown in Fig. 2. A vertically reciprocable rod 43 is attached to a lever 44 which pivots about the axis of rod 40. This lever is connected to casting 41 by means of a rib 45 on the latter. At weft exhaustion the rod 43 moves down to raise the fingers 42, the result of which is to elevate one or the other of the slides 11 or 12. As usually constructed, if the color slide is forward, in the right hand position as viewed in Fig. 1, the slide 11 will be raised, but if the slide is back, or to the left, as shown in Fig. 1, then the rear slide 12 will be raised.

The dog 16 of the raised slide will project over the shelf 17 and at a later point in the cycle of the loom when rod 43 is raised, the previously raised slide will be depressed if the shuttle corresponding thereto is to be active on the next pick thereby moving a bobbin toward transfer position. Upper and lower lugs 46 and 47, respectively, on the slides, cooperate with the fingers 42 to produce the vertical movements of the slides 11 and 12. Release mechanisms commonly called cradles and designated generally at 48 are provided, one for each vertical slide, and serve to advance the bobbins toward transfer position.

Front and back bobbin supports 49 and 50 are provided to hold in transfer position any bobbin released by the devices 48, the rear support 50 preferably being yieldable as is usual, and being close enough to support 49 to hold the smaller of the bobbins.

The matter thus far described is either of common construction, or has been proposed heretofore, and forms no part of my present invention. For a further understanding of the operation of the magazine reference may be had to Patent No. 1,030,748. It is sufficient for the purpose of the present invention to state that at the time of transfer the rod 27 will be raised through the action of a dog 16 so that the latch will lie in the path of the dagger on the lay, this general concept being the same as that found in practically all multicolor weft replenishing looms operating in this country.

In the type of loom to which my invention more particularly relates the shuttles are of two different sizes, being designated herein as S and C, respectively, corresponding to silk and cotton shuttles. The bobbins are also of different sizes, the small bobbin B being held in the silk shuttle S, while the large bobbin L' is carried by the large cotton shuttle C.

In carrying my invention into effect I alter the casting 41 and one of the parts forming the yielding lock for the control member, and also provide a new form of latch. Inasmuch as the transerrer arm is to be given two different movements depending upon which character of bobbin is to be transferred, I provide the latch with top and bottom notches 60 and 61, respectively, which are at different

distances from the pivot 62 which connects the latch holder with the transerrer arms 29. The bunter on the lay in the present instance is of usual construction, being secured to the lay so that it can enter either of the notches.

When the dagger enters the top notch 60 which is relatively near the pivot 62 the transerrer arm will be given a relatively short downward motion such as will position a large bobbin L' in the large cotton shuttle C. On the other hand, when the dagger enters the lower notch 61 which is farther from the pivot 62 the transerrer arm will be given a greater motion, such as is needed to transfer one of the small bobbins B into the small silk shuttle S.

The means for determining which of the notches 60 or 61 shall coat with the lay bunter is in the present instance located at the upper part of the magazine and comprises a finger 70 carried by the lever 23 and projecting downwardly, as shown in Fig. 2. This finger is adapted for cooperation with one or the other of two different positioning surfaces 71 and 72 cast integral with or otherwise carried by the part 41. These surfaces are at different distances from the axis of the shaft 40 and therefore are able to stop the lever 23 in either of two positions, depending upon the longitudinal position of the color slide, which in turn determines which of the surfaces is to be engaged by the finger 70.

The relatively high surface 71 coacts with the finger 70 to give the rod 27 a relatively low position the effect of which is to render notch 60 operative with the dagger. It is this notch which gives the relatively short motion of the transfer for the cotton shuttle and surface 71 therefore corresponds to the front cell 14 and front slide 11 and is positioned to the left of the low surface 72.

When the finger 70 rests on the low surface the lever 23 will receive a relatively larger left hand motion the effect of which is to position the rod 27 in its high transfer position to place notch 61 in the path of the bunter 32. In the following transfer, therefore, the arm T will receive a relatively large motion to transfer the small bobbin into the small shuttle.

It is to be understood that the color slide is moved to the right to cooperate with vertical slide 11 and under these conditions the high surface 71 will coact with the finger 70. When the color slide is moved to the left, or in the position shown in Fig. 1, however, the fingers 42 are so disposed as to coact with the vertical slide 12, and under these conditions the low surface 72 will be under the finger 70.

While I have shown an invention in connection with a loom coacting with only two colors, yet it will be understood that the relatively high and low surfaces which coact

with the finger 70 are independent of each other, although moving together, and the invention is therefore not limited to two colors. It will further be seen that the particular mode of controlling the transferrer arm set forth herein is to alter the latch, but the effect of this alteration is to bring about two different relations between the lay and the transferrer arm one of which gives the arm a relatively long motion and the other of which gives a short motion. I do not wish to be limited to the use of the double notched latch in order to accomplish this result.

It is to be understood that the surfaces 71 and 72 are preferably concentric with the axis of the color slide shaft 40 and are of sufficient length to permit a limited angular movement of the color slide when in contact with the finger 70, and it is to be understood further that the rocking movement of the color slide at the time of weft detection which occurs on transferring beats of the loom will take place after the customary shuttle feeler not shown starts to reset the control member 18. This relation avoids wearing of the finger by the surfaces 71 and 72.

From the foregoing it will be seen that I have provided means for giving the transferrer arm two different degrees of motion depending upon the size or character of the bobbin to be transferred and the shuttle to receive it. It will further be seen that this control is exercised through a longitudinally moving member which has surfaces of two different heights, these surfaces being effective to relate the lay and the transfer mechanism under two different conditions each of which will give the transferrer arm a different amount of motion. More specifically, the surfaces have been mounted on the lower slide and the control exercised through the yielding lock for the control member 18 together with the rod which normally lifts the latch, and the latter is provided with notches of different depths or distances from the axis 62. The invention also contemplates the provision of means to move bobbins to two different positions at the conclusion of the transfer stroke, regardless of the size of the shuttles.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom for weaving a fabric having two different wefts and operating with a large bobbin for one weft and a small bobbin for the other weft, transfer mechanism to transfer either size bobbin, and means to give the transfer mechanism

different degrees of motion depending upon the size of the bobbin being transferred.

2. In a weft replenishing loom for weaving a fabric having two different wefts and operating with a large bobbin for one weft and a small bobbin for the other weft, transfer mechanism to coact with the bobbins, and means to advance a selected bobbin to transfer position and also control the amount of motion of the transfer mechanism to give the said transfer mechanism a movement proportional to the size of the bobbin being transferred.

3. In a weft replenishing loom operating with bobbins of different sizes, means to select a bobbin of any of said sizes for transfer, and a transferrer arm under control of said means and effective by virtue of said control to move different amounts depending upon the size of the bobbin being transferred.

4. In a weft replenishing loom for weaving a fabric having two different wefts and operating with a large bobbin for one weft and a small bobbin for the other weft, a transferrer arm, a lay, and means dependent upon the size of the bobbin being transferred to relate the lay and transfer arm in different ways to give the latter varying degrees of motion depending upon the size of the bobbin being transferred.

5. In a weft replenishing loom operating with bobbins of two different sizes, a transferrer arm, a lay, and means to relate the lay and transferrer arm in two different ways one of which gives the transferrer arm a relatively long motion and the other of which gives a relatively short motion depending upon which size bobbin is being transferred.

6. In a weft replenishing loom operating with bobbins of different sizes, a transferrer arm, an actuator to move the arm, and means to select a bobbin for transfer and effective to relate the actuator and transferrer arm to cause different movements on the part of the arm depending upon the size of the bobbin being transferred.

7. In a weft replenishing loom operating with bobbins of different sizes, a transferrer arm, an actuator to move the arm, a movable device assuming different positions depending upon which size of bobbin is to be transferred, and means controlled by the device to relate the actuator and transferrer arm under different conditions effective to give said arm varying degrees of motion depending upon the size of the bobbin being transferred.

8. In a weft replenishing loom operating simultaneously with large and small bobbins, a transferrer arm, and means to give said transferrer arm a relatively large motion when transferring a small bobbin and a relatively small motion when transferring a large bobbin.

9. In a weft replenishing loom for weav-

ing a fabric having two different wefts and operating with a large bobbin for one weft and a small bobbin for the other weft, a transerrer arm, an actuator to move the arm, a latch to be operatively related to the actuator, and means to relate said latch to the actuator in two different ways one of which gives a larger movement to the transerrer arm than the other.

10 10. In a weft replenishing loom for weaving a fabric having two different wefts and operating with a large bobbin for one weft and a small bobbin for the other weft, a transerrer arm, an actuator to move the arm, 15 a transerrer latch connected to the arm to be operatively related to the actuator, and means to place the latch and actuator in two relative positions one of which is effective to give the transerrer arm a relatively long motion and the other of which is effective to give the transerrer arm a relatively short motion.

In testimony whereof I have hereunto affixed my signature.
